UNITED STATES PATENT OFFICE.

THOMAS P. ANTHONY, OF EDGEWATER PARK, NEW JERSEY.

METHOD AND APPARATUS FOR FORMING PIPE MOLDS.

Application filed May 6, 1921. Serial No. 467,271.

To all whom it may concern:

Be it known that I, THOMAS P. ANTHONY, a citizen of the United States of America, and resident of Edgewater Park, in the 5 county of Burlington and State of New Jersey, have invented a certain new and useful Improvement in Methods and Apparatus for Forming Pipe Molds, of which the following is a true and exact description, reference being had to the accompanying drawings, which form a part thereof.

My invention relates to the manufacture of dry sand molds for casting pipes. As such molds have heretofore been made the 15 mold for the outside of the pipe and the core for the inside of the pipe have been made separately, separately coated with blacking and separately dried before being assembled together to form a complete mold 20 for the casting of a pipe. The object of my invention is to provide a method whereby the mold and core can be made simultaneously and simultaneously coated with blacking and dried without at any time removing 25 the core from the mold or shifting the core and mold with relation to each other to such an extent as will risk the contact of the core with the mold and consequent injury to the mold surface.

30 Broadly speaking, my invention consists in assembling together in proper relationship to each other a flask, a core bar and a shell pattern having the shape of the body of the pipe compacting, molding sand of 35 the character required to make a dry sand mold in the space between the pattern and the flask and between the pattern and the core bar, preferably by jarring and withdrawing the shell pattern longitudinally, 40 leaving the mold and core formed and in properly spaced relationship to each other.

I effect the blacking of the surface of the 45 mold and core by pouring a liquid mixture of blacking into the annular space, separating them, the water being largely absorbed into the sand and the blacking being deposited on the surface of the sand in sufficient 50 quantity to avoid the risk of adherence between the molten metal and the molding sand and the mold and core being formed and blacked as above described. I then simultaneously dry them by passing drying gases through the annular spaces separating them after which drying the assembled mold 55 and core are ready for casting.

In casting pipes if the bell end flanges are otherwise so formed that longitudinal shell pattern will not give the required form to the end or ends of the pipe I use in addition to the shell pattern supplemental patterns shaped to give the desired form to the end or ends of the pipe and so secured in position that they can be withdrawn longitudinally and after the withdrawal of the shell pattern and supplemental patterns I insert 60 in the end or ends of the mold such end forming cores as will give the inside of the pipe ends the desired form.

In most cases it will be convenient and some times necessary that the formation of 70 the body portion of the core and of the mold, to shift the core and mold longitudinally with respect to each other so as to leave a clear and sufficient space open at both ends for the passage downward of the blacking 75 mixture and the passage either upward or downward of the drying gases used to dry the mold and the core, and such necessary or desirable shifting, never very great in extent, can be readily effected without any 80 danger of the core coming in contact with the mold, the parts, of course, being returned to normal position with reference to each other after the drying of the mold.

In the formation of the mold and core as 85 above described and particularly where the compacting of the sand is effected on a jarring machine, it is desirable that the sand forming the top of the core could be compacted by ramming and for this purpose I 90 provide an annular ramming and sand holding ring shaped so as to fit fairly closely between the core bar and the shell pattern and which can be inserted after the jarring of the mold and used to ram the upper layer 95 of sand forming the core and then located in position so as to hold the sand of the core while the shell pattern is being withdrawn. This device has also the function of guiding and centering the shell pattern while it is 100 being withdrawn.

The molds formed by my pattern are intended to be poured from the top of the mold and it is necessary, therefore, that the core shall be carried up to or above the top 105 of the flask and to further steady the motion of the shell pattern while being withdrawn I secure to the top of the flask an upwardly extending guide ring through which the shell pattern moves and which not only 110

- 22 aids in preventing lateral motion of the pattern while being withdrawn from the mold but will continue to hold it in proper alignment after it has passed above the flask.
- 5 This guide ring will conveniently form a part of the supplemental end pattern used in the upper end of the mold where the use of such a shell pattern is necessary or advisable.
- 10 My invention and the best means and devices for carrying it into practical use will be best understood as described in connection with the drawings in which it is illustrated and in which
- 15 Figure 1 is a sectional elevation of one side of a mold showing a flask and core bar in assembled position on a ramming seat with the shell pattern in position and the supplemental bell pattern of the mold in position in the upper end of the flask and in contact with the shell pattern, the ramming seat is shown as resting on the table of the jarring machine and the sand compacted on each side of the pattern to form the flask and core.
- 20 Figure 2 is a similar section of the mold with the withdrawal of the shell and bell patterns show the core as sufficiently elevated to make a clear passage from the top to the bottom of the mold and showing a bucket pouring the blacking mixture into the top of the mold. The mold in this construction is raised on a casting seat.
- 25 Figure 3 is a sectional elevation of the same character as Figure 1 showing the arrangement of the parts when the bell of the pipe is to be raised at the bottom of the mold.
- 30 Figure 4 shows a flask and core formed as in Fig. 3 after removal of the shell pattern and the supplemental pattern used at the top of the flask with the mold shown as slightly raised above the casting seat, showing also the appliances used for drying the mold and core.
- 35 Figure 5 is a view showing the arrangement of parts where a flanged pipe is to be cast.
- 40 Figure 6 showing the mold and core after the withdrawal of the patterns with the core raised and supplemental core in place on the casting seat.
- 45 Figure 7 is a view generally similar to the construction shown in Fig. 4 but with provision made for the introduction of drying gases at the top of the mold, and
- 50 Figure 8 is an elevation of a table mold with the core shown as raised and provision made for passage of heating gases upward through one mold and downward through the second mold.
- 55 A indicates the flask having, as shown, in Figs. 1, 2 and 8, a flared end A' at its top over the bell end of the mold and, as shown in Figs. 3, 4 and 7, a flared end A³ at the bottom where the bell is to be formed at the bottom of the mold. In these figures the upper end of the flask is also shown as flared at A⁴ and in Figs. 5 and 6 which show the preparation of a mold for a flanged pipe the flask is flared both at top and bottom as indicated at A⁵ and A⁶. B, Fig. 1, indicates a ramming seat which, as shown, rests upon the jarring table M and a jarring machine not shown in detail and upon which rests the flask. On the inside the ramming seat has a conical seat indicated at B', below which extends a number of centering lugs indicated at B², the function of which is to hold the core iron properly centered when the core is raised, as shown in Fig. 2. C indicates the core iron which can be of any usual construction and generally made collapsible where used in casting of large pipes. Toward the lower end it is formed with a slight taper as indicated at C' and a keyway C² is formed through its lower portion and another keyway C³ formed through its upper portion. C⁴ is a key used as shown for holding the core iron in position during the drawing of the shell pattern. D is the shell pattern of cylindrical form having, as shown in Fig. 1, a seat D' for a rubber bead ring, the ring in place being indicated at E. At D² I have indicated the presence of some holes through the top of the shell pattern through which it can be engaged by a hoisting device. F is the core supporting ring externally of cone shape to fit on the seat B' of the ramming and casting seat B and internally shaped to fit on the tapered portion C' of the core iron on which it forms a jamming fit. G, Fig. 1, is a separable portion for conforming the mold to the designed bell shape. This pattern forms a fit with the shell pattern D and is supported on top of the flask by the laterally extending arms G². G' is an upwardly extending annular guide surface formed as shown integral with the pattern G. H is a ramming and sand holding annulus of a size to fit between the core iron of the shell pattern and provided with upwardly extending handle rods H². The lower face of the rammer H is shown as beveled outwardly and downwardly. I is a pin which can be inserted through the hole C³ in the core iron and used to lock the rammer H in position while the shell pattern is being withdrawn. J, J', indicate respectively the molds and the core compacted on each side of the patterns.
- 55 In Fig. 3, B³ indicates the ramming seat formed, as shown, with an annular seat B⁴ to receive and center the bell pattern indicated at G² with the top of it as indicated at G³. The bell pattern makes a tapering fit in this construction, the conically fixed sand supporting ring indicated at F² is attached to the core bar by bolts indicated at

Q. N is an annular plate fitting on top of the ramming seat, as shown, and P is a separate portion for forming a flare at the upper end of the mold and like the bell pattern G it is formed with an upward extension P' for guiding the shell pattern supported on top of the flask by arms indicated at P². In Fig. 4 the mold made as indicated in Fig. 3, is shown as removed from the jarring seat and supported above the chill plate R by small blocks indicated at S. R' indicates a seat on the core plate in which is seated the core iron R² which supports the molding sand or clay indicated at J², J³ indicating molding sand or clay directly supported in a cavity of the chill plate. K indicates the hood extending over the top of the core iron and supported on the top of the flask and T indicates a pipe through which drying gases are admitted to the center of the core iron.

In Fig. 5 the flask is shown supported on a ramming seat B⁵ having a detachable portion B⁶ on the inside of which are formed annular tapered seats for the end of the shell pattern D and for the sand supporting ring F, the upper portion of the ramming seat and its extension B⁶ serving as a pattern for the formation of the lower part of the mold. P, P, indicate the pattern for the formation of the upper portion of the mold supported on arms P, P² and having a guide extension PP' and in Fig. 6 the mold is shown as transferred to the casting seat R, R, which is formed to support the core ring G⁵.

The construction shown in Fig. 7 is, generally speaking, similar to the construction shown in Fig. 4 except that provision is made for the introduction of drying gases at the top of the mold. T' indicates the pipe through which the drying gases are led from a place of origin and delivered into a channel U through which they pass from opening U' and the passages U², U⁴, into the top of the mold, U³ indicating a cover plate used in this construction to close the top of the core iron.

The molds shown in Fig. 8 are generally similar to the molds shown in Fig. 1, the arrangement being one in which two molds are formed in a single flask and in which a cover K² fits over the top of the flask so as to form a conduit from the top of one mold to the top of the other. T² indicates a gas pipe for the heating gases located at the bottom of one of the molds and in this construction the hollow core irons are covered as indicated to prevent the heating gases from passing freely through them.

Referring first to Figs. 1 and 2, the flask, core iron and shell pattern are assembled together, as shown in Fig. 1, the separable pattern G being also secured in place and the rubber bead ring E being also in place, as

shown in Fig. 1. The flask and core supporting ring and, in this construction, the shell pattern, rest upon the ramming seat B and the core iron is held down in place by the wedge C⁴. The ramming ring H is, of course, not used until the core is practically completed.

Sand is fed into the top of the mold and in the spaces between the shell pattern and the core iron and the mold and core are formed simultaneously and of like material by ramming the sand preferably by the action of a jarring machine the table of which is indicated at M.

As the molten metal is by my process intended to be poured into the top of the mold the core sand J' is built up higher than the top of the flask and at the top is preferably rammed more compactly and given the proper shape by the insertion of the ramming ring H which by means of the handles H² can be used to ram and tamp down the sand and give it the proper form at the top. After being used, the ring H is locked in position by the insertion of a pin or key I through the hole C³ as indicated in Fig. 1.

After the mold and core has been formed as above described the shell pattern D is withdrawn, being guided in its upward movement by its contact with the portion G and its extension G' and by its contact with the outer surface of the annular ramming ring H so as to leave the mold sand on each side of it engaged. As the shell pattern moves up the rubber bead ring E is detached from it and by reason of its elasticity contracts, leaving contact with the sand in which it has formed a proper cavity for the bead at the bottom of the pipe. The pattern G is removed from the mold after the withdrawal of the shell pattern and the core is then raised as indicated in Fig. 2 permitting the easy removal of the rubber bead ring and leaving a clear passage from the top to the bottom of the mold as indicated. Care must, of course, be taken to keep the core centered and for this purpose the guide lugs B² acting in connection with the lower end of the core iron are very useful. The core is held in the position indicated in Fig. 2 by any convenient means, as shown by a spider K².

The parts being in the position shown in Fig. 2, the mold and core are next blacked which can be easily accomplished by pouring a mixture of blacking and water into the top of the mold, the mixture resting over the sand of the mold and core. The water is more or less absorbed in the sand and a sufficient coating of blacking is left upon the surface.

The mold, having been blacked, it is next necessary to dry it and this I accomplish by passing heated gases through the spaces between the core and the mold as shown in

Fig. 2. The heated gases issue from a pipe T^2 and pass upward through the cavity, simultaneously drying the sand in both the mold and the core.

- 5 The mold having been dried, the core is lowered into the proper position with the ring F in contact with the centering conical surface B' of the ramming and casting seat B . A proper core is inserted in the bell
 10 end of the mold and the mold is then poured and after the metal has set the core iron is drawn out of the mold leaving behind it the sand supporting ring F after which the casting
 15 is drawn from the mold.
 15 In the construction shown in Fig. 3 where the bell is formed at the bottom of the mold the pattern G^2 is properly centered on the ramming seat B^3 and fitted against the lower end of the shell pattern D , the core sand
 20 supporting ring F^2 fitting against a centering surface of the pattern G^2 . The portion P is secured in place at the top of the mold and sand introduced and properly compacted preferably, as before, by the jarring
 25 machine indicated at M , the core being clamped to the ramming seat by clamps as indicated at O . After the sand has properly compacted on both sides of the bell pattern and on the outside of the Patterns G^2 and P ,
 30 the shell pattern is withdrawn as before described, the ramming seat and pattern G^2 are removed and the casting or chill plate R with the core iron R^2 centered in it and brought to proper position with regard to
 35 the core while the flask as shown in Fig. 4, is slightly elevated and held in elevated position by blocks S . While in this position the mold and core are blacked as already described after which the hood K is placed
 40 over the top of the mold and the mold and core bar are brought over a drying gas supply pipe T which, in this construction, delivers the heating gases through the center of the core iron and then directed by the
 45 hood K downward through the cavity between the core and the mold and out through the space between the bottom of the flask and the chill plate. After the mold is dried the flask is lowered to position on the chill
 50 plate and casting made.

In the construction shown in Figs. 5 and 6, the parts being in the position shown in Fig. 5, the sand is compacted to form a mold and core. The ramming seat and pattern
 55 P , P , and D are then removed, the flask is placed on the casting plate R , R , which, in this construction, supports the flanged core G^5 ; the core is elevated, the mold and core blacked and dried in the same way already
 60 described, the core then returned to casting position and the casting made.

The description already given as to Figs. 3 and 4, of course applies to Fig. 7, the only difference being that in this construction the top of the hollow core iron is cov-

ered by the plate U^3 and drying gases introduced through pipe T' into the top of the mold through the described passages U' in the hood K' .

The operation in the case of the construction shown in Fig. 8 is the same as that described with reference to Figs. 1 and 2, the only difference being that in this construction the two molds have their tops connected by the hood K^2 and the drying gases introduced through the pipe T^2 pass upward through one mold and downward through the other.

Having now described my invention, what I claim as new and desire to secure by Letters Patent, is:

1. The method of forming a mold for casting pipe which consists in assembling a flask and core bar together with a shell pattern for forming the body portion of the pipe, compacting molding sand in the spaces on both sides of the shell pattern to form the mold and core, removing the shell pattern, adjusting the mold members so as to leave an open-ended vertical passage between mold and core, pouring a liquid blacking mixture in the space between the mold and core to black the mold and passing drying gases through the space between the mold and core to simultaneously dry both members of the mold.

2. The method of forming a mold for casting pipe which consists in assembling a flask and core bar together with a shell pattern for forming the body portion of the pipe, compacting molding sand by jarring in the spaces on both sides of the shell pattern to form the mold and core, removing the shell pattern, adjusting the mold members so as to leave an open-ended vertical passage between mold and core, pouring a liquid blacking mixture in the space between the mold and core to black the mold and passing drying gases through the space between the mold and core to simultaneously dry both members of the mold.

3. The method of forming a mold for casting pipe which consists in assembling a flask and core bar together with a shell pattern for forming the body portion of the pipe and a separable pattern or patterns forming a continuation of the shell pattern for forming the portions of the mold which are not formed by the shell pattern, compacting molding sand in the spaces on both sides of the shell pattern and on the outside of the separable patterns to form the mold and core, removing the patterns, adjusting the mold members so as to leave an open-ended vertical passage between mold and core, pouring a liquid blacking mixture into the space between the core and mold to black them, passing drying gases through the space between the mold and core to dry both members simultaneously and inserting supple-

mental mold sections in the spaces left by the separable patterns to give final form to the mold.

4. The method of forming a mold for casting pipes which consists in assembling a flask and core bar together with a shell pattern for forming the body portion of the pipe and a bell pattern fitting on and forming a continuation of the shell pattern and shaped to give the desired bell form to the outside of the mold only, compacting molding sand in the spaces on both sides of the shell pattern and on the outside of the bell pattern to form the outside of the mold and the core of the body portion of the pipe mold removing the bell pattern and shell pattern and inserting a socket core in the bell of the mold.

5. The method of forming a mold for casting pipes which consists in assembling a flask and core bar together with a shell pattern for forming the body portion of the pipe and a bell pattern fitting on and forming a continuation of the shell pattern and shaped to give the desired bell form to the outside of the mold only, compacting molding sand in the spaces on both sides of the shell pattern and on the outside of the bell pattern to form the outside of the mold and the core of the body portion of the pipe mold removing the bell pattern and shell pattern, adjusting the mold members so as to leave an open-ended vertical passage between mold and core, pouring a liquid blacking mixture in the space between the mold and core and inserting a socket core in the bell of the mold.

6. The method of forming a mold for casting pipes which consists in assembling a flask and core bar together with a shell pattern for forming the body portion of the pipe and a bell pattern fitting on and forming a continuation of the shell pattern and shaped to give the desired bell form to the outside of the mold only, compacting molding sand in the spaces on both sides of the shell pattern and on the outside of the bell pattern to form the outside of the mold and the core of the body portion of the pipe mold, removing the bell pattern and shell pattern, adjusting the mold members so as to leave an open-ended vertical passage between mold and core, passing drying gases through the space between the mold and core to simultaneously dry both members of the mold.

7. The method of forming a mold for casting pipes which consists in assembling a flask and core bar together with a shell

pattern for forming the body portion of the pipe and a bell pattern fitting on and forming a continuation of the shell pattern and shaped to give the desired bell form to the outside of the mold only, compacting molding sand in the spaces on both sides of the shell pattern and on the outside of the bell pattern to form the outside of the mold and the core of the body portion of the pipe mold, removing the bell pattern and shell pattern, adjusting the mold members so as to leave an open-ended vertical passage between mold and core, pouring a liquid blacking mixture in the space between the mold and core, passing drying gases through the space between the mold and core to simultaneously dry both members of the mold, and inserting a socket core in the bell of the mold.

8. The method of forming a mold for casting pipes which consists in assembling a flask and core bar together with a shell pattern for forming the body portion of the pipe and a bell pattern fitting on and forming a continuation of the shell pattern and shaped to give the desired bell form to the outside of the mold only, compacting molding sand by jarring in the spaces on both sides of the shell pattern and on the outside of the bell pattern to form the outside of the mold and the core of the body portion of the pipe mold, removing the bell pattern and shell pattern and inserting a socket core in the bell of the mold.

9. In an apparatus for simultaneously forming a dry sand mold and core substantially as described the combination with a core iron and a shell pattern surrounding it of an annular tamping and sand holding ring fitting between the core and pattern and means for holding said ring on the core iron while drawing the shell pattern.

10. In an apparatus for simultaneously forming a dry sand mold and core, substantially as described, the combination with the flask and shell pattern of an upwardly extending shell pattern guide secured to the top of the flask and extending above the same.

11. In an apparatus for simultaneously forming a dry sand mold and core substantially as described, the combination with the flask and shell pattern of a pattern extending down into the upper end of the flask and having an upwardly extending guide for centering the shell pattern as it is withdrawn from the flask.

THOMAS P. ANTHONY.
